UNITED STATES PATENT OFFICE.

LOUIS B. HASBROUCK, OF ELMIRA, NEW YORK, ASSIGNOR TO ECLIPSE TEXTILE DEVICES, INC., OF ELMIRA, NEW YORK, A CORPORATION OF NEW YORK.

DYEING APPARATUS.

Application filed April 8, 1926. Serial No. 100,486.

This invention relates to dyeing apparatus and the like, and aims to provide means for impregnating predetermined parts of an absorbent mass in the liquid.

5 A particular object of the invention is to provide a machine for spotting yarn while the yarn is wound in a mass of the type customarily known as a cone of yarn.

A device embodying the invention is especially adapted for impregnating predetermined parts of a cone of yarn with a liquid such as water or an aqueous dyeing solution which does not spread readily in fibrous material, although certain features of the invention may be applied also when a rapidly spreading liquid such as an alcohol dyeing solution is used.

Particular objects of the invention are to inject liquid simultaneously at closely spaced points of the portion of the mass to be dyed, to inject liquid into separated portions of the mass in such manner that a portion of larger volume receives more liquid than a portion of less volume, and to insure 25 the penetration of a substantial amount of the liquid into the part of the mass close to the core on which it is wound. In addition the invention provides an improved holder for a cone of yarn.

30 The invention may best be understood by a detailed description of a practical machine embodying it. Such a machine is shown in the accompanying drawings, in which:—

35 Fig. 1 is a plan view;

Fig. 2 is a side elevation of the pump showing parts sectioned on the line 2—2 of Fig. 1;

40 Fig. 3 is a side elevation of the pump and work holder sectioned on the lines 3—3 of Figs. 1 and 2;

Fig. 4 is a plan view sectioned on the line 4—4 of Fig. 3;

45 Fig. 5 is a vertical section on the line 5—5 of Fig. 4 showing one of the injectors; and

Fig. 6 is a perspective view of one of the chucks for holding the injector needles.

The device as shown in the drawings is provided with a base plate B which may be supported at about the height of an ordinary work bench by means not shown in the drawings. On the plate B are mounted a pump P and a work-holder W. In the op-

eration of the machine the pump draws 55 liquid from a reservoir, not shown in the drawings, and forces it into predetermined portions of a cone of yarn on the work-holder through injectors J, J' mounted on a header H fixed to the cylinder of the pump.

The pump P has a vertical cylinder P¹ 60 whose bore P² is closed at its lower end by a plug P³ containing a drain opening P⁴ communicating with the valve controlled drain pipe P⁵ extending through the plate B. The piston P⁶ of the pump is driven from a shaft P⁷ mounted on the lower side of the plate B and driven through a punching press clutch so that it may be given a single revolution when desired by the operator. The piston is connected with a crank P⁸ on the shaft P⁷ by means of a lever P⁹ and a connecting rod P¹⁰. The rod P¹⁰ may be attached at different points of the lever P⁹ to vary the length of the stroke of the piston.

70 The inlet opening P¹¹ of the pump cylinder is controlled by a check valve P¹² which may be located in an intake pipe P¹³ connected to the opening P¹¹. The intake pipe 75 P¹³ leads from a reservoir for the liquid dye (not shown) which may be located below the plate B.

80 The outlet opening P¹⁴ of the pump cylinder communicates directly with the header H which is mounted on the cylinder.

85 The header H contains two crossing bores H¹, H². One end of the bore H¹ communicates with the discharge opening P¹⁴ of the pump while the other end is closed by a plug H³. A check valve H⁴ seated in the bore H¹ prevents the return of liquid from the header to the pump during the up-stroke 90 of the piston to the pump. The ends of the bore H² are closed by plugs H⁵, H⁶, the latter of which is adjustable for a purpose hereinafter explained. The bore H² is provided with two lateral openings H⁷, H⁸ in which are mounted the injectors J and J'.

95 The injector J comprises a triple nozzle J¹ and three needles J² fixed in the discharge 100 openings of the nozzle. The nozzle J¹ has a body J³ on the rear end of which is a threaded stem J⁴ which is screwed into the hole H⁷ in the header. The stem J⁴ contains an axial bore J⁵ which is the intake 105 opening of the nozzle J¹. The body J³ of the nozzle has a flange J⁶ which is seated

- against the front surface of the header H. In an enlarged bore in the front portion of the body J³ is located a chuck J¹⁰ containing three longitudinal bores J¹¹ whose outer 5 ends form the discharge openings of the nozzle J¹. To permit contraction of the inner portions of the bores J¹¹ in order to grip the needles therein, the rear portion of the chuck contains a diametrical slit J¹² at the inner end of which is a transverse bore J¹³ extending across the three bores J¹¹, and transverse slits J¹⁴. The chuck J¹⁰ is retained in the body J³ by a nut J¹⁵ which is screwed on the front end of the body and 10 engages the chuck J¹⁰ so as to force the conical inner end J¹⁶ of the chuck against a conical seat in the body. The chuck J¹⁰ has at its outer end three projecting collars J¹⁷ which are thrust into the mass to be dyed when the mass is brought into operative relation with the injector. On the outer end of the nut J¹⁵ is an annular projection J¹⁸ lying some distance behind the outer ends of the collars J¹⁷.
- 25 Each of the needles J² has a solid rear end portion J¹⁹ which is clamped in the inner portion of one of the bores J¹¹ of the chuck by screwing the nut J¹⁵ inward. As the shaft of the needle is of uniform diameter, it may be gripped at any point by the chuck so that the distance which it projects beyond the end of its collar J¹⁷ may be varied.
- 30 The needle J² has a pointed front, whose apex J²⁰ is on the axis of the needle. The needle contains an open longitudinal groove J²¹ which extends from the portion of the needle crossing the bore J¹³, as nearly as possible to the apex J²⁰.
- 35 The injector J' is identical with the injector J except that in the form shown its needles J² have axial bores J²² extending through their rear portions J¹⁹ instead of having solid rear portions like the needles J².
- 40 The injector needles which have been described are not claimed herein as they form the subject matter of my divisional application, filed March 14, 1927, Serial No. 175,081.
- 45 The work holder W comprises a carriage W¹ carrying a standard W² in which a shaft W³ is rotatably mounted. On one end of the shaft W³ is a cone holder W⁴ adapted to carry a cone of yarn C on which such a cone is ordinarily wound. The cone holder W⁴ engages the core C¹ of a cone of yarn only near its ends, thus leaving a free space inside the core. The cone holder has a rod W⁵ of materially less diameter than the core C¹ of a cone of yarn carrying at its outer end an adjustable plunger W⁶ having a frusto-conical head W⁶' for engaging the core of such a cone at or near its smaller end. At the inner end of the rod
- 50 W⁵ is a gripping member W⁷ for engaging the larger end of the core. The member W⁷ has a threaded outer surface which forms a corresponding thread in the inner surface of the card-board core C¹ when the core is screwed upon it.
- 55 The cone holder which has been described is not claimed herein as it forms the subject matter of my divisional application, filed March 14, 1927, Serial No. 175,082. 75
- 60 The carriage W¹ is reciprocable in directions parallel to the needles J², J²', and adjustable transversely to the needles. The carriage is slidably mounted on rods W⁸ fixed on a frame W⁹ which is mounted on a transverse rod W¹⁰ adjustably secured in standards W¹¹ projecting up from the plate B. A shaft W¹² rotatably mounted in similar standards W¹³ assists in supporting the frame W⁹ and provides for reciprocating the carriage W¹ on the rods W⁸. For this purpose the shaft W¹² is provided with a gear W¹⁴ meshing with a rack W¹⁵ on the bottom of the carriage. A handle W¹⁶ is provided for turning the shaft W¹². 80 85 90
- 95 The shaft W³ and the cone holder W⁴ are rotated through a small arc at each reciprocation of the carriage by means of a ratchet wheel W¹⁷ fixed on the shaft W³ and a pawl W¹⁸ carried by a bar W¹⁹ fixed to the outer ends of the rods W⁸. Further rotation of the shaft W³ may be obtained by turning a hand wheel W²⁰ also fixed on the shaft W³.
- 100 In the use of the machine, the carriage W is first retracted to the position shown in Fig. 1 and a cone of yarn C is mounted on the cone holder W⁴. After the plunger W⁶ has been adjusted in accordance with the length of the cones to be dyed, a cone may be mounted on the cone holder very quickly and easily as it is necessary only to slip its core over the rod W⁵ and then screw the larger end of the core upon the threaded member W⁷ until the inner end of the core is brought into firm contact with the head W⁶'. The carriage is then moved towards the injectors by turning the handle W¹⁶ until its movement is arrested by an adjustable stop W²¹. This causes the needles J², J²' to penetrate the yarn and forces the collars J¹⁷ into the outer portion of the yarn so as to compress it above the outer ends of the needles, as shown in Fig. 3. The piston P⁶ of the pump is then given a single reciprocatory movement which forces liquid previously drawn into the cylinder of the pump through the header H and the injectors J, J' into the portion of the cone of yarn immediately surrounding the needles of the two injectors. The carriage W¹ is then returned to the position shown in Fig. 1. The pawl and ratchet W¹⁸, W¹⁷ cause a slight rotation of the cone C during the latter part of this movement. The operation is then repeated until two 110 115 120 125 130

separated zones C^2 , C^3 of the cone of yarn are completely saturated with the dyeing solution.

It will be noted that because of the juxtaposition of the needles of each injector and the large number of teeth on the ratchet J^{17} , the liquid is injected at numerous closely spaced points, so that the dyeing may be effected by means of the solution which does not spread readily, for example, an aqueous dyeing solution. Such a solution may be evenly distributed throughout the depth of the mass. This is accomplished by the compression of the outer portion of the mass surrounding the needles by means of the collars J^{17} which prevents an excess of liquid in the outer portion of the mass, and by extending the needles so that the outer ends of their grooves J^{20} reach substantially to the surface of the core of the mass. To accomplish this it may be necessary to let the needles project so far that their apexes J^{19} enter the core C^1 , as shown in Fig. 4, or pierce the core, as shown in Fig. 3. This can be done without injury to the needles, owing to the fact that the cone holder W^4 leaves a free space within the core into which the points of the needles may project.

A substantially uniform saturation of the yarn in the two zones dyed is obtained by forcing a greater quantity of liquid into the zone C^2 which has a larger diameter and consequently a larger volume than the zone C^3 . The difference in the quantities injected into the two zones is obtained by giving the liquid a freer passage to the grooves of the needles J^2' than to those of the needles J^2 . It will be noted that the liquid may enter the grooves of the needles J^2 directly through the axial bores J^{22} in the rear ends of these needles, while to enter the grooves of the needles J^2' the liquid must pass through the slot J^{12} in the chuck so as to enter the grooves J^{21} through the transverse bore J^{13} . The flow of liquid to the injector J may be further restricted to the exact extent desired by means of the adjustable plug H^8 , as clearly indicated in Fig. 4.

What is claimed is:

1. In a machine of the class described, means for causing liquid to penetrate simultaneously into two zones of a cone of yarn so arranged that a greater amount of the liquid is injected into the zone having the larger circumference.

2. In apparatus of the class described, the combination of a support for a cone of yarn, means for causing a limited quantity of liquid to penetrate simultaneously into two zones of a cone on the support, so arranged that more than half the quantity enters the zone of the larger circumference.

3. In apparatus of the class described, the combination of a support for a cone of yarn, two injectors directed toward different zones

of a cone on said support, a pump, and means providing passages connecting said pump with said injectors, the passage leading to the injector directed towards the zone of less circumference being more obstructed than the other passage so that less than half the liquid from the pump passes therethrough.

4. In apparatus of the class described, the combination of a support for a cone of yarn, two injectors directed toward different zones of a cone on the support, a pump, means providing passages connecting the pump with the injectors, and adjustable means for partially obstructing the passage leading from the pump to one of the injectors.

5. In apparatus of the class described, the combination of a support for a cone of yarn, two injectors directed toward different zones of a cone on the support and each consisting of a nozzle and a grooved needle projecting therethrough, and pressure means communicating with both injectors, the needle of the injector directed toward the zone of less circumference having a solid rear end, while that of the other injector has a rear end containing an axial bore leading directly into its groove.

6. In apparatus of the class described, two injectors each comprising a body, a slotted chuck located therein, and a grooved needle held in the chuck, and pressure means in communication with the rear ends of the bodies of both injectors, the rear portion of the needle of one injector being solid so that liquid entering its groove must pass through the slot in the chuck, and the rear portion of the needle of the other injector containing an axial bore so that liquid may pass directly into its groove.

7. In apparatus of the class described, the combination with a support for holding a cone of yarn, and means for simultaneously injecting a limited quantity of liquid at a plurality of points in each of two separated zones of a cone on the support.

8. In apparatus of the class described, an injector comprising a plurality of nozzles, grooved needles projecting from said nozzles, and an annular projection surrounding the nozzles and having its outer surface spaced inwardly from the outer ends of the nozzles.

9. In apparatus of the class described, an injector comprising a body, a chuck in said body containing a plurality of longitudinal bores, collars at the front end of the chuck surrounding said bores, needles held in said bores and projecting from said collars, and a nut engaging the chuck and the body and having its front surface spaced inwardly from the ends of said collars.

10. In apparatus of the class described, the combination of a support for a cone of yarn, means for injecting a limited quantity

of liquid into two zones of a cone on said support, means for regulating the amount of liquid injected, and means for regulating the proportion of said amount entering each zone.

11. In apparatus of the class described, the combination of a holder for a cone of yarn formed to support the cone by engagement with the ends of its core and leaving a free space inside the middle part of the

core, a needle containing an open groove, means for causing relative movement between the needle and the cone to cause the needle to penetrate through the yarn and into the core, and means for forcing liquid into the yarn through the groove of the needle.

In testimony whereof I have hereunto set my hand.

LOUIS B. HASBROUCK.
